UNITED STATES PATENT OFFICE.

CHARLES LEVEY, OF TORONTO, ONTARIO, CANADA, ASSIGNOR TO EDWARD GURNEY, OF SAME PLACE.

DESIGN FOR A HOT-WATER OR STEAM RADIATOR.

SPECIFICATION forming part of Design No. 19,627, dated January 28, 1890.

Application filed December 6, 1889. Serial No. 332,712. Term of patent 14 years.

To all whom it may concern:

Be it known that I, CHARLES LEVEY, engineer, a subject of the Queen of Great Britain, residing at the city of Toronto, in the county 5 of York, in the Province of Ontario, Canada, have invented and produced a new and original Design for Hot-Water or Steam Radiators, of which the following is a specification, reference being had to the accompanying drawings, forming part thereof.

Figure 1 represents a perspective view of my newly-designed radiator arranged as the two arms of a right angle. Fig. 2 is a cross-section through one of the water-legs.

15 The leading features of my design consist in a series of vertical legs arranged in a single line in the position of and practically occupying no more space than the ordinary base-board or wainscot.

20 A represents the exterior walls of the vertical water legs or chambers. These water legs or chambers are arranged in a single vertical row, connected together by horizontal water-chambers located at the top and bottom 25 of the row. It will be observed that the exterior wall of each vertical water leg or chamber is triangular in form for the greater portion of its length, the apex of the triangle extending beyond the circular walls B, which

30 inclose the horizontal water-chambers. The apex of the upper portion of the walls A is removed. The outer surface of the walls of

the legs or chambers A, as well as the walls of the chambers B, are suitably ornamented by raised fancy ornamentation, substantially 35 as shown.

Immediately above the radiator formed by the series of water legs or chambers, arranged substantially as described, I fix a deflecting-plate C, forming an upper finish.

40 Each end of the radiator is finished by an ornamental vertical screen c, and the bottom of the radiator is finished by an ornamental base D.

What I claim is—

45 1. In a design for a radiator, the shape of the same, comprising a single row of triangularly-shaped chambers united at top and bottom by horizontal chambers, substantially as herein shown.

50 2. The design for radiators herein shown and described, consisting of a single row of vertical legs or chambers united at the top and bottom by horizontal connections, surmounted by a deflecting-plate, and having 55 end screens substantially in line with the vertical chambers and in harmony with their exterior design, as set forth.

Toronto, October 25, 1889.

CHAS. LEVEY.

In presence of—

CHARLES C. BALDWIN,
E. CUMMINGS.
